UNITED STATES PATENT OFFICE.

HENRY E. PARSON, OF NEW YORK, N. Y.

COMBUSTION-REGULATOR FOR LOCOMOTIVE-FURNACES.

SPECIFICATION forming part of Letters Patent No. 742,130, dated October 20, 1903.

Original application filed July 22, 1902, Serial No. 116,586. Divided and this application filed December 15, 1902. Serial No. 135,312. (No model.)

To all whom it may concern:

Be it known that I, HENRY E. PARSON, a citizen of the United States of America, and a resident of the city and State of New York, ⁵ have invented certain new and useful Improvements in Combustion - Regulators for Locomotive-Furnaces, of which the following is a specification.

This application is a division of my application, filed July 22, 1902, Serial No. 116,586.

This invention relates to an improvement in the structural formation of a locomotive-furnace.

In a pending application, filed July 22, 1902, ¹⁵ Serial No. 116,586, I have described and claimed means for increasing the grade of combustion in the locomotive fire-box and the automatic regulation of such means.

In carrying out the details of my above-mentioned invention it has been found necessary to vary the structural formation of the furnace, and hence the present invention is directed to such changes arranged and constructed in the manner best adapted for the ²⁵ use intended.

The preferred form of construction is illustrated in the accompanying drawings, in which—

Figure 1 is a side elevation of a locomotive, ³⁰ parts broken away for better disclosure. Fig. 2 is a detail view of the mechanism for regulating the force of the exhaust.

Referring to the drawings, 1 represents the fire-box closed, and which is the usual feed-door 2.

3 represents the grate, comprising a fixed section 4 and a movable section 5. The fixed section is provided with the usual water-tubes 6 and comprises in the grate proper a series ⁴⁰ of detachable sections 7, grooved along their edges, as at 8, to encompass the water-tubes, the grooves terminating in an upwardly-tapered opening 9. The movable grate-section 5 may be of any well-known grate construction. The grate herein described has been found to best serve the purposes desired and is shown herein for that reason. However, as the grate structure forms the subject-matter of a separate pending application, Serial ⁴⁵ No. 135,311, and no claim thereto is made

herein it is to be understood that I contemplate the use of any desired construction of grate, simply requiring a fixed section arranged to permit the passage of a forced draft and a movable or swinging section. ⁵⁵

The movable or swinging grate-section 5 is hinged at 10 to the front wall of the fire-box contiguous the feed-door 2 and is suitably operated through the medium of a hand-lever 11, having an inwardly-extending arm 12, the ⁶⁰ free end of which is connected to the grate-section 5 through a link 13.

An ash-pit 14 of closed type underlies the fire-box, as illustrated, and is arched at 15 to accommodate one of the main axles. The ⁶⁵ arching of the pit practically divides the same into two compartments 16 and 17, each of which is provided with a door 18 and 19 to permit of the removal of ashes when desired.

A blower 20, comprising a series of injectors, which may be of the usual or any preferred type, directs the currents for the forced draft, and as such draft must be delivered below the grate it follows that some means must be provided for properly distributing ⁷⁰ such draft without interfering with the ashes in the pit 14. The desired means I provide through the use of an auxiliary ash-receptacle 21, which lies within the plane of pit 14, but only beneath the fixed grate-section 4. The receptacle comprises a closed box-like structure having a bottom 22 inclined upwardly in a rearward direction. As the blower 20 is positioned to direct its blast against this bottom, the inclination of the latter serves to spread the ⁷⁵ blast beneath the entire bed of fuel resting upon the fixed grate-section 4, thus evenly distributing the current, as is highly desirable.

The injector is fixed in a housing 23, mounted on the front wall of the receptacle 21, the air-admission opening of which (the housing) is provided with the usual damper 24, suitably controlled by rod 25, projecting within reach of the operator. The forced-draft blower is suitably controlled by means automatically ⁸⁰ operated by a predetermined pressure of the engine - boiler, such pressure operating through lever and valve mechanism 26 to start or shut off the supply of steam to the injectors. As this construction forms the ⁸⁵ 100

subject - matter of the application first referred to herein, it will not be further described, as for the purpose of the present invention any means of controlling the injectors 5 may be used. I have found it desirable to control the force of the draft by manual means in order to draw the gases of combustion through the fire-tube with sufficient force to prevent back pressure in the fire-box and 10 the escape of gases from the furnace-door when it is opened.

The means referred to above comprise an extension 27, secured to the top of the usual exhaust-pipe, to which extension is telescopically fitted a pipe 28. A rack 29, fixed to 15 the latter pipe, is adapted to be engaged by a pinion 30, mounted on a shaft 31, which shaft extends beyond the boiler of the locomotive and is provided with a fixed arm 32, 20 connected to a handle-rod 33, disposed in position to be conveniently operated. Bell-shaped deflectors 34 are mounted below the lower end of the stack surrounding pipe 28 to direct the escaping exhaust - steam into 25 the stack and to produce an induced draft through the fire-tubes. The usual deflector 34 is provided to direct the escaping products of combustion from the boiler-tubes to the screen 35, through which they pass to the 30 lower open ends of the bells 34. As pipe 28 is raised or lowered through the medium of the rack and pinion it will be evident that the mouth of said pipe 28 will be raised out of or lowered into the bells and the induced 35 draft will be greater or less. The effective power of such forced and induced drafts may

be thus controlled and the best results obtained.

The ashes accumulating from the fuel are drawn forward onto the swinging grate-section 5, whence through the operation of lever 11 they may be dumped into the compartment 16 of ash-pit 14, and when the latter is filled, or practically so, the ashes may be forced back into compartment 17, doors 18 or 19 permitting removal when desired.

The structure described is specially adapted for use with my forced-draft apparatus described in application Serial No. 116,586, but is capable of variations and changes 50 without departing from the spirit of my invention, and I desire it to be understood that I consider all such as within the scope of my invention.

What I claim as new is—

In a locomotive, the combination of a closed fire-box provided with an ash-pit, a grate, a smoke-box, a receptacle beneath the grate having an inclined bottom, said receptacle being out of communication with the ash-pit, means for directing a blast against the inclined bottom near the lower end thereof, and in a direction opposite to the flow of the products of combustion from the fire-box, and means for creating a draft in the smoke-box, 65 substantially as described.

Signed by me at New York city, New York, this 8th day of December, 1902.

HENRY E. PARSON.
